PACKAGING DEVICE AND METHOD

Frederick H. Meendsen, Garden City, N. Y., assignor to International Paper Company, a corporation of New York

Application February 3, 1938, Serial No. 188,408

2 Claims. (Cl. 226—18)

My present invention relates to the packaging of commodities and, more particularly, to the packaging of commodities in paper bags.

Many commodities are of a yieldingly resilient nature and are exceedingly bulky when relaxed or unconfined. Such commodities may be greatly reduced in bulk with only a moderate amount of pressure. In the packaging of such commodities, it is desirable to reduce the bulk thereof to the greatest practicable extent. Such reduction in bulk effects appreciable economies in container cost and in storage, handling and shipping charges. Such reduction in bulk also produces firm, sightly packages which are desirable from a merchandising standpoint.

A great amount of difficulty has been experienced in packaging commodities of the type above discussed in flexible containers, such as paper bags. While the commodities may be reduced in bulk by manual manipulation and progressively inserted into the bag, the expansion of those portions of the commodities within the bag produces frictional resistance which renders further insertion difficult and frequently results in wrinkling or tearing of the bag walls.

Commodities of the type discussed above include woven, knitted or felted fabrics and articles made therefrom, such as sweaters, hosiery and other articles of clothing, blankets, et cetera. Many other commodities fall within this classification, as, for example, steel or other artificial wool, natural wool, cotton batting, yarn and the like. For convenience in description, all commodities of this general type will be hereinafter referred to as compressible material.

It is an object of my invention to provide a simple and efficient method of packaging commodities of the class described.

It is a further object of my invention to provide a simple and efficient mechanism which will facilitate the packaging of commodities of the class described.

According to my invention, I provide an expandible form of rigid material which is adapted to be positioned within a flexible container, such as a paper bag. The form is caused to expand to open and support the bag in opened position. Commodities may be packed, to any desirable degree of compactness, into the form. The form is provided with a suitable opening communicating with the interior of the bag whereby the bag and the commodities packed in the form may be removed from the form. The package thus formed may be closed or sealed,

if so desired, in any suitable or convenient manner.

Other objects and advantages of my invention will become more apparent from a consideration of the following description of a preferred but obviously not necessarily the only form of my invention together with the drawings accompanying and forming a part of the present specification.

In the drawings,

Fig. 1 is a side elevational view of a device constructed according to my invention, partly in section and having portions broken away for clarity;

Fig. 2 is a perspective view illustrating the manner of placing a bag in position upon the device of Fig. 1;

Fig. 3 is a rear perspective view of the device of Fig. 1 illustrating the removal of a filled bag therefrom;

Fig. 4 is a side elevational view of a modified form of my invention; and

Fig. 5 is an elevational view of the opposite side of the device illustrated in Fig. 4.

Similar characters of reference indicate similar parts throughout the several views.

Referring now to the drawings, there is shown a form 10 comprising two sections 11 and 12 made of any suitably rigid sheet or molded material. The two sections 11 and 12 are suitably interconnected to form the hollow body 10 with cross-sectional dimensions substantially equal to the cross-sectional dimensions of the container with which the form 10 is designed to cooperate. The sections 11 and 12 are so interconnected as to provide for contraction and expansion of the form 10 whereby an empty container may be readily placed thereon and held in opened position.

As shown in the drawings, the sections 11 and 12 include telescoping flanged portions 13 and 14 which are pivotally interconnected by suitable bearing members such as rivets 15 and 16. The flanged portions 13 and 14 are cut away as shown at 17 and 18 at points below the pivots 15 and 16 in order to provide openings in the sides of the form 10. The flanged portions may continue in gradually diminishing size toward the bottom of the form 10 in order to rigidify the structure. The lower portions of the front and rear walls 19 and 20 of sections 11 and 12 are tapered as shown at 21 and 22 to facilitate the introduction of a container upon the form.

The sections 11 and 12 above the pivots 15 and 16 form a hollow chute having front and

5 rear walls 19 and 20 and telescopic side walls comprising the overlapped flanges 13 and 14. The upper portions of the walls forming this chute may be flared outwardly as shown in the drawings to facilitate the introduction of commodities therein. The extensions of walls 19 and 20 below the pivots 15 and 16 constitute blades or plates which, together with the flanges thereon, form the bag opening and holding portion of 10 my device.

10 A contractile spring 23 is stretched between suitable supports 24 and 25 located respectively upon the sections 11 and 12. The spring 23 tends to maintain the form 10 in expanded position as shown in Fig. 1. A suitable stop 26 is provided upon the section 12 in a position to be abutted by the flange 14 upon section 11 and serves to limit the expansion of the form 10 under the influence of spring 23.

15 The device thus far described may be supported in any convenient manner upon a wall or other available surface. For convenience in manipulation of the device it is desirable to support the same in a position spaced from the supporting 20 surface. Thus, I have shown a spacing block 27 which is secured to one of the form sections and which may be secured to a supporting surface. As shown in the drawings, the block 27 may comprise a rectangular tube having stiffening flanges 28 at its ends. The tube or block 27 may be secured to the form 10 as by rivets 29 or by spot-welding, brazing or any other suitable means. The unit comprising form 10 and block 27 may be secured to a supporting surface 30 W by suitable fastening means such as screws.

35 It will be understood that the interior surfaces of the form 10 should be smooth and unobstructed. To this end the rivets 15, 16 and 29 and the inner ends of pins 24, 25 and 26 should be made flush with the inner surface of the form or should be smoothly rounded.

40 The use of my invention in the packaging of compressible material will now be set forth.

45 A form 10 is provided having a cross-sectional area, when expanded, slightly greater than that of the particular bag or container which it is desired to use. The length of those portions of the form which extend below the block 27 should be approximately equal to the height of the bag. As shown in Fig. 2, the section 11 is rocked about the pivots 15, 16 against the tension of spring 23 to bring the lower ends of sections 11 and 12 together. This operation places the form 10 in collapsed or contracted condition 50 and an empty bag may be slipped upon the tapered ends 21, 22 and drawn upwardly outside the form 10. The operation just described may be conveniently performed by applying pressure to the front wall 19 of the form 10 through the front wall of the bag 31 and maintaining such 55 pressure while the bag is drawn upwardly into operative position. Pressure upon the wall 19 may now be released and the form will expand under the influence of spring 23 to bring the walls 19 and 20 into substantially parallel relationship and into engagement with the inner surfaces of the bag 31 to open and support the same in opened position upon the form as shown in Fig. 1. It will be apparent from a consideration of Fig. 1 that the bag 31 may be drawn 60 upon the form to a position wherein the mouth of the bag is substantially in contact with the block 27 as shown or that the bag may be drawn upwardly to any lesser extent desired.

65 Commodities 32 of compressible material may

now be inserted into the flared upper portions of the form 10 and may be packed to any practical degree of tightness if so desired. The commodities are forced downwardly through the passageway formed by the chute and bag holding portion into the interior of bag 31.

70 As shown in Fig. 3, the bag 31 and the commodities 32 may be removed from the form by inserting the fingers of the operator into the openings provided by the cut-away portions 17, 10 18 of the flanges 13, 14 and drawing downwardly upon the bag and commodities therein. Frictional contact between the walls 19, 20 and the inner surfaces of the bag may be relieved by exerting pressure upon the plate 19 as indicated 15 by the position of the thumb in Fig. 3.

75 It will be understood that the section 11 may be rocked about its pivots to cause contraction of the form 10 in any convenient manner. For example, it may be desired to grasp the upper 20 edge thereof for this purpose.

80 In Figs. 4 and 5, I have illustrated a modification of my device. In the form shown in these figures, various adjustments have been provided for the purpose of adapting my device for use 25 with bags of various sizes. The sections 11' and 12' of the form 10' are pivotally united as by rivets 33 which secure the section 11' to a pair of plates 34. The plates 34 are mounted upon the section 12' for adjustment relative thereto. To this end, the plates 34 are provided with slots 35 and the section 12' has fixed thereon bolts 36 which are adapted to enter the slots 35. The bolts 36 have threaded thereon wing nuts 37 which may be tightened to hold the plates 34 35 in adjusted position relative to the section 12'.

85 Adjustment of the plates 34 results in a change of cross-section of the form 10' in the plane of the pivots 33 and may be availed of to adapt the form 10' for the reception of bags of various 40 cross sections.

90 A contractile spring 38 is stretched between suitable supports located respectively upon the sections 11' and 12', as shown in Fig. 5. The support 39 located upon section 12' may conveniently be in the form of a post or stud. In order that the tension of the spring 38 may be controlled in accordance with the adjustment of cross-section of form 10', the opposite end of the spring 38 is adjustably connected to the section 11'. As shown in the drawing, this adjustable support comprises a lug 40 secured to the section 11'. The lug 40 has a bore therein threaded for the reception of a threaded element 41. The element 41 has an annular portion of reduced diameter indicated at 42. A collar 43 is confined within this reduced annular portion and is freely rotatable relative to the element 41. The collar 43 has an offset portion adapted for reception of one end of the spring 60 38. The element 41 is provided with a finger grip portion 44 by which the element may be conveniently rotated for adjustment in the tension of spring 38.

95 Expansion of the form under the influence of 65 the spring 38 is limited by an adjustable stop comprising an abutment member 45 secured to the section 12' and a threaded stop element 46 adjustably carried by a suitable support 47 secured to the section 11'.

100 The form 10' is supported by a spacing member 27' similar in all respects to the spacing member 27 described above in connection with Figs. 1, 2 and 3.

105 In the use of the device just described, the 75

cross-section of the form 10' is adjusted in accordance with the cross-section of the bag which it is desired to use. To this end, the adjustable pivots 33 are moved to such position that the chute portion above the pivots 33 and the plates or blades 19' and 20' will form a continuous passageway having a cross-section substantially equal to the cross-section of the bag when the blades 19' and 20' are substantially parallel.

5 The stop, 45, 46 is adjusted to permit the section 11' to rock about the pivots 33 to such an extent that the bag engaging portions of the form will tend to expand to a cross-section slightly greater than that of the bag when fully opened. The 10 tension of the spring 38 is adjusted by manipulation of the element 41 and should be so selected as to firmly hold a bag thereon without exerting sufficient expansive force to result in tearing of the bag. The adjustment of the stop 45, 46 insures the expansion of the form to an extent sufficient to hold the bag thereon and at the same time prevents the form from opening to an undesirable extent when the bag is removed therefrom. The use of this form of my invention in 15 the packaging of materials in flexible containers is the same in all respects as the use of the form shown in Fig. 1 as hereinbefore described.

20 From the above description it will be apparent that I have provided a method and means for packaging commodities which fulfills the objects of my invention. While the above detailed description of a preferred form of my invention has been made in compliance with statutory requirements, it will be obvious that modifications 25 and variations in details and modes of use may be resorted to by those skilled in the art. It is, therefore, my intention that such description shall be taken in an illustrative rather than in a limiting sense and that the scope of my invention shall be limited only by the appended claims.

I claim:

1. In a bag filling and holding device, a material-receiving chute having opposed front and rear walls and having side walls comprising telescoped flanges extending from said front and rear walls, bearing members adjacent the bottom of said chute and pivotally uniting said flanges, said bearing members being adjustable whereby the cross-section of said chute may be varied,

the front and rear walls of said chute extending beyond said bearing members to form blades adapted to be inserted within the bag to be filled, said blades being substantially coextensive with opposite walls of said bag, spring means yieldably urging said blades to rock about said bearing members into substantially parallel relationship against the walls of said bag to hold the latter on said blades in opened position, means for varying the tension of said spring means in accordance with variations in cross-section of said chute, said flanges extending beyond said bearing members whereby to form a passageway from the chute to the interior of said bag, and portions of said flange extensions having edges in opposed spaced relation to provide an opening through which the material within the bag may be engaged to hold said material in the bag upon removal thereof from said blades.

2. In a bag filling and holding device, a material-receiving chute having opposed front and rear walls and having side walls comprising telescoped flanges extending from said front and rear walls, bearing members adjacent the bottom of said chute and pivotally uniting said flanges, 25 said bearing members being adjustable whereby the cross-section of said chute may be varied, the front and rear walls of said chute extending beyond said bearing members to form blades adapted to be inserted within the bag to be filled 30 said blades being substantially coextensive with opposite walls of said bag, spring means yieldably urging said blades to rock about said bearing members into substantially parallel relationship against the walls of said bag to hold the latter on said blades in opened position, means for varying the tension of said spring means in accordance with variations in cross-section of said chute, adjustable stop means for limiting 35 the rocking of said blades about said bearing members, said flanges extending beyond said bearing members whereby to form a passageway from the chute to the interior of said bag, and portions of said flange extensions having edges in opposed spaced relation to provide an opening through which the material may be engaged 40 to hold said material in the bag upon removal thereof from said blades.

FREDERICK H. MEENDSEN.
